PHOTOGRAPHIC LIGHT UNIT

Lester A. Dine and Edgar S. Lemmey, Levittown, N. Y.

Application May 7, 1958, Serial No. 50,794

Term of patent 14 years

(Cl. D61—1)

Figure 1 is a perspective view of a photographic light unit, showing our new design;

Figure 2 is a front elevational view, to an enlarged scale;

Figure 3 is a side elevational view, to an enlarged scale, the opposite side being substantially a mirror image thereof; and

Figure 4 is a rear elevational view thereof, to an enlarged scale.

A portion of the connecting cord and the connector have been omitted from Figures 2, 3 and 4 for convenience in illustration. The characteristic features of our

new design reside in the parts thereof shown in solid lines. The broken line showing of a representative support for the unit in Figure 1 is for illustrative purposes only.

We claim:

The ornamental design for a photographic light unit, substantially as shown and described.
